UNITED STATES PATENT OFFICE.

FREDERICK H. BEROLD, OF WYOMING, OHIO.

PRINTER'S BLOCK.

1,107,647.

Specification of Letters Patent. Patented Aug. 18, 1914.

Application filed December 11, 1911. Serial No. 665,065.

To all whom it may concern:

Be it known that I, FREDERICK H. BEROLD, a citizen of the United States, residing at Wyoming, in the county of Hamilton and 5 State of Ohio, have invented certain new and useful Improvements in Printers' Blocks, of which the following is a specification.

My invention relates to printers' blocks 10 arranged for clamping thereon an electro-type or other plate from which printing is to be done, and the invention has for its object the provision of a block of this character which is extensible in length and width 15 in novel manner.

My invention consists in novel means whereby support is given to the plate at all the corners thereof, when an extension has been made; further in novel means for locating 20 insert-strips employed in making extensions; further in providing a multi-part extension block consisting of a plurality of main block-sections each of which is arranged to be extended in a given direction, 25 the block-sections being arranged for having separating means placed therebetween for adjusting the distance between the block-sections; and in novel arrangement of separating means extending in integral form 30 crosswise of the insert-strips employed in extending each of said block-sections.

The invention will be further readily understood from the following description and claims, and from the drawings, in which 35 latter:

Figure 1 is a plan view of my improved device, with the plate removed. Fig. 2 is an edge elevation of the same looking in the direction of the arrow 2 of Fig. 1. Fig. 3 is 40 an edge elevation of the same looking in the direction of the arrow 3 of Fig. 1. Fig. 4 is a cross-section of my improved device taken on the irregular line 4—4 of Fig. 1, with the plate shown in position. Fig. 5 is a cross- 45 section of my improved device taken on the irregular line 5—5 of Fig. 1, the same being partly broken away, and the plate in position. Fig. 6 is a cross-section of my improved device on the line 6—6 of Fig. 1. Fig. 7 is a detail in cross-section on the line 50 7—7 of Fig. 1. Fig. 8 is a cross-sectional detail on the line 8—8 of Fig. 1. Fig. 9 is a cross-sectional detail on the line 9—9 of Fig. 1, showing the plate supported by the adjustable corner. Fig. 10 is a perspective 55 view of one of the main extension strips.

Fig. 11 is a perspective view of one of the auxiliary extension strips; and, Fig. 12 is a perspective view of one of the crossing extension strips.

23 and 24 are primary blocks. These primary blocks are arranged to have supplemental blocks 25 and 26 secured thereto respectively, provision being made for the reception of insert-strips 27 between the blocks 25 and 23, and the reception of corresponding insert-strips 28 between the blocks 26 and 24. One or more of each of these insert-strips may be employed. The supplemental block 25 has a plate-retaining lip 29 thereon and the primary block 24 has a plate-retaining lip 30 on the same. A main block-section 21 is thereby formed by the primary block 23, its supplemental block 25 and the insert-strips 27, and a main block-section 22 is formed by the primary block 24, its supplemental block 26 and the insert-strips 28. 60 These respective block-sections are extensible in a given direction, instanced as a lateral extension by the insert-strips 27, 28, respectively. The block-section 22 is preferably auxiliary to the block-section 21. The insert-strips 27 are each provided with a groove 31 at one side thereof and with a tongue 32 at the other side thereof. The blocks 23 and 25 are provided with coacting 65 tongue and groove, the tongue being shown on the block 25 at 40, and the groove in the block 23 at 41. (See Figs. 7 and 10.) These tongues and grooves extend longitudinally 70 of the strips, and are arranged so that any 75 of the tongues may be received in any of the grooves for locating and definitely positioning the parts in height. For longitudinally 80 positioning the parts, (see Figs. 1 and 7), I provide each of the insert-strips with a 85 pin 33 and a hole 34, one of the coacting 90 blocks, instanced as the block 23, being provided with a similar hole 43 and the other of said blocks, instanced as the block 25, 95 being provided with a similar pin 44, these 100 holes and pins registering with each other so that the blocks and the insert-strips are readily located lengthwise with relation to each other.

36 is a screw received through a hole 37 in the supplemental block 25 and in a threaded bearing 38 in the primary block 23. (See 105 Figs. 1 and 4.) Two of these screws are shown. The insert-strips 27 are provided with bottomless recesses 39 for being readily 110 received over the screws.

The locating and clamping means between the parts of the auxiliary block-section 22 are similar to the locating and clamping means of the primary block-section 21, corresponding parts being designated by similar but primed reference numerals. (See Figs. 1, 3, 6 and 11.)

The insert-strips 27 are preferably of lengths equal to the blocks 23 and 25, and the insert-strips 28 are preferably equal in lengths to the blocks 24 and 26.

For providing extension of the printer's block in a direction at right angles to the extensions provided for the main block-sections, (see Figs. 1, 2, 5, 8, 9 and 12), I provide insert-strips 46 arranged to be received between the main block-sections, these insert-strips preferably being received integrally across the pieced portions of said main block-sections, the main block-sections being arranged to be clamped together with said insert-strips between them for completing the finished printer's block. One or more of the insert-strips 46 may be employed.

The insert-strips 46 are preferably made in various lengths corresponding to the completed width of the printer's block. Each of the insert-strips 46 is provided with a tongue 47 at one side thereof and with a groove 48 at the other side thereof, the main block-sections being provided with a coacting tongue and groove, the tongues in the present instance being on the primary block 24 and on the supplemental block 26, as shown by the tongues 49, 50, and the grooves being in the primary block 23 and supplemental block 25, as shown by the grooves 51 and 52. These tongues and grooves form means for locating and maintaining the parts at equal height, so that the top of the printer's block may at all times be of proper and uniform height for receiving and supporting the plate, shown at 45, and printing properly. For accommodating these tongues, the ends of the insert-strips 27 adjacent thereto are provided with notches 58.

For locating the insert-strips 46 longitudinally, I provide each of the same with a pin 53 projecting from one side thereof and a hole 54 in the other side thereof, one of the blocks 23, 24, being provided with a similar pin, as shown by the pin 55 on the block 24, the other of said blocks being provided with a hole 56. These pins and holes register with each other for positioning said blocks and insert-strips in correct lateral relation. The ends 57 of said insert-strips beyond said pins and holes vary according to the width or number of insert-strips used for lateral extension and extend integrally across the latter for definitely locating all the parts in proper heights and imparting rigidity to the finished block.

For clamping the main block-sections together I provide a screw 60. (See Figs. 1,

3 and 5.) The screw is received through a hole 61 in the primary block 24 and into a threaded bearing 62 in the primary block 23. The insert-strips 46 are provided with bottomless recesses 63 for being readily received over and removed from the screw 60.

The primary block 23 is provided with adjustable lips 65 for clamping the plate between said adjustable lips and the lips 29, 30. (See Figs. 1, 2, 3 and 5.) The lips 65 are shown on slides 66 received in slots 67 in the primary block 23 and adjusted by means of screws 68 having toothed wheels 69 thereon, the said screws having threaded connection with said slides. The inner end of each of these screws is formed as a stud 71 received in a bearing 72 in the said primary block, its outer end being formed as a stud 73 journaled in a bearing 74 of a bearing-strip 75 let into the edge of said primary block and secured to said primary block by screws 76. The primary block 23 is provided with a rabbet 81. The primary block 24 is provided with a rabbet 82 and each of the insert-strips 46 is provided with a rabbet 83, for forming a continuous rabbet for permitting a usual rack-strip to be moved lengthwise thereof throughout the length of the form for operating all of the wheels 69 in line therewith.

The primary block 23 is provided with a rabbet 84. The supplemental block 25 is provided with a rabbet 85 and each of the insert-strips 27 is provided with a rabbet 86, these rabbets being in line with the wheels 69 extending crosswise of the form, so that the rack-strip may be passed longitudinally of all said mating rabbets for clamping the plates to their several blocks.

My improved device permits a form containing a number of my improved printers' blocks to be unlocked without disturbing the integrity or adjustment of the blocks or loosening the plates therefrom, and provides definite lines along which the plates are fastened. It further provides means whereby any one or all of the plates in a form may be removed or replaced without disturbing the make-up of the form. My improved device further supports the plate at all corners thereof, and provides a uniform support for the plate throughout the area thereof.

Having thus fully described my invention, what I claim as new and desire to secure by Letters Patent, is:

1. A printer's block made up of a plurality of main block sections, each of which comprises a primary block and a supplemental block of substantially the shape of a parallelogram, and insert strips between said primary and supplemental blocks, the supplemental blocks of both sections being of substantially the same width, and the insert strips being of less width, means in each of

said main block sections for clamping the said component parts thereof together, and means for positioning said main block sections at greater or less distance apart, and 5 for positively clamping them together.

2. A printer's block comprising a plurality of substantially rectangular main extensible sections each comprising means for adjustably extending the same in a given direction, and means extending integrally across 10 said last-named means in each of said main extensible sections for adjustably separating said main extensible sections.

3. A printer's block comprising a plurality 15 of main block-sections each of which comprises a pair of plate-supporting blocks, each of said blocks being of substantially the shape of a parallelogram, means for adjusting the distance between said blocks and 20 means for clamping said blocks together, and means for adjusting the distance between said clamped main block-sections and clamping said clamped main block-sections together.

25 4. In combination in a printer's block comprising a plurality of main block-sections each comprising a plurality of block-parts, an insert-strip or strips, and means for securing said insert-strip or strips between said 30 block-parts, an insert-strip or strips between said plurality of main block-sections and extending integrally across said first-named insert-strip or strips in each of said main block-sections, and means for securing said 35 main block-sections together with said second-named insert-strip or strips between them.

40 5. A printer's block comprising a plurality of main block-sections, each of said main block-sections comprising a pair of plate supporting blocks, means for adjusting the

distance between said plate supporting blocks in a given direction, and means for clamping said plate supporting blocks together; insert strips for adjusting the distance between said main block sections in a direction substantially at right angles to 45 said first named direction, and clamping means crossing all of said strips and having connection with each of said main block 50 sections, and serving to hold said parts together.

6. A four-cornered printer's block comprising a plate-supporting block at each corner of said printer's block, and insert- 55 strips received in crossing relation at substantially right angles to each other between said plate-supporting blocks for adjusting diagonally opposite ones of said plate-sup- 60 porting blocks toward and from each other in directions both of the length and of the width of said printer's block, the said insert- strips extending in one direction integrally across the said insert-strips extending at substantially right angles thereto. 65

7. In combination, a printer's block comprising a pair of main composite sections, each section being made up of primary and supplemental blocks, with insert strips between them, and an additional set of insert 70 strips located between said main composite sections and extending integrally across all of said first mentioned strips and blocks, the end of such first mentioned strips abutting against said additional strips on each side. 75

In testimony whereof, I have hereunto signed my name in the presence of two sub-scribing witnesses.

FREDERICK H. BEROLD.
